DEVICE FOR FOOT PROTECTION

Filed Nov. 4, 1930

UNITED STATES PATENT OFFICE

ALBERT A. STRAUSS, OF PITTSBURGH, PENNSYLVANIA

DEVICE FOR FOOT PROTECTION

Application filed November 4, 1930. Serial No. 493,427.

This invention relates in general to shoe guards, and in particular to that type of shoe guard worn by steel workers and others engaged in kindred occupations.

5 In many places where workers are employed heavy weights are handled which are sometimes dropped on the feet of the workers and thus effect much injury. In other places molten metal is handled and is 10 prone to splash on the workers' feet and stick to the instep and toe portions thus inflicting bad burns.

15 Among the objects of the present invention are to provide a novel and efficient shoe guard including a metal shield covering the instep and toe and to so arrange the metal shield that it will at all times be supported throughout its extent free from the shoe to which it is applied; to provide such a shield with a 20 longitudinal strengthening rib; and to provide a flexible support for the shield arranged to distribute the shock due to a falling body all over the front part of the wearer's foot so as to minimize the local effect of such falling body.

25 With the above and other objects in view one embodiment of the invention will now be described in detail and specifically claimed, reference being had to the accompanying drawing, wherein:

Figure 1 is a side elevation of the device applied to a shoe.

Figure 2 is a plan view of the device.

30 Figure 3 is a section on the line 3—3 of Figure 2 with the device applied to a shoe.

In the embodiment of the invention here disclosed there is provided a rigid metal shield 5, preferably formed from a single piece of sheet metal having side edges 10 converging from the rear or instep portion of the shield to the front or toe portion thereof. The front edge 11 of the shield is convexly curved and the rear edge 12 is concavely curved, as is shown in Figure 2. This metal 45 sheet is arched transversely throughout its length. The lateral arched portions 13 thus formed, are united to a central arched portion 14 by reversely curved portions 15. The central arched portion 14 is more abruptly 50 arched than the lateral portions 13 so that

this central arched portion forms a longitudinally extending strengthening rib. It will be noted from Figure 3 that the metallic shield is of greater width than the shoe S to which it is applied. The rear edge 12 is 55 upwardly curved as in Figure 1 to prevent cutting of the shoe or foot in case the shield is forcibly driven backwards.

In connection with this shield there is employed a flexible member 16 of leather or 60 other suitable material which conforms in general shape to the shield but is of greater width than the latter and projects rearwardly from beneath the shield. Rivets 17 secure the side portions of the shield to the flexible member 16 adjacent its side edges but the member 16 is maintained sufficiently taut between the riveted portions so that the shield arches up from the flexible member as shown in Figure 3. Thus, the flexible member contacts with the upper forward part of the shoe, while the metallic shield is held in spaced relation thereto throughout. Under these conditions a blow received anywhere on the shield will not be localized on a definite part 65 of the foot of the wearer but will, by the flexible and somewhat yieldable member, be 70 well distributed.

An instep strap 18 extends laterally from one side of the member 16 at its rear and 75 is arranged to pass beneath the arch of the shoe S and to have its end received by a buckle 19 carried by the other side of the member 16. Similarly an ankle strap 20 extends rearwardly from one side of the member 16 to pass around the ankle portion of the shoe and be engaged in a buckle 21. Obviously, by means of these straps and buckles the device may be readily applied to and removed from the shoes. 80

I claim:

1. A shoe guard comprising an integral metallic shield adapted to extend over the instep and toe of a shoe, and a flexible cushioning member secured to the under side of said shield and interposed between the shield and the shoe when in position, said cushioning member maintaining the shield spaced from the shoe at all points, and means for securing the guard to a shoe. 85

2. A shoe guard including a metallic shield adapted to fit over the instep-portion of a shoe and having a width greater than the shoe, a flexible fabric member secured adjacent its side edges to the side edges of the metallic shield and adapted to rest on the shoe, said shield being held away from the shoe by said member and being arched to lie in spaced relation to the member above the shoe, and means to secure the member in position on the shoe.
3. A shoe guard including a metallic shield adapted to fit over the instep-portion of a shoe and having a width greater than the shoe, a flexible fabric member secured adjacent its side edges to the side edges of the metallic shield and adapted to rest on the shoe, said shield being held away from the shoe by said member and being transversely arched upwardly from the member between the attached portion of the guard and member, and means to secure the member in position on the shoe.
4. A shoe guard including a metallic shield adapted to fit over the instep portion of a shoe and having a width greater than the shoe, a flexible fabric member secured adjacent its side edges to the side edges of the metallic shield and adapted to rest on the shoe, said shield being held away from the shoe by said member and being transversely arched upwardly from the member between the attached portion of the guard and member, the central portion of the shield being more abruptly arched than the lateral portions to form a longitudinally extending stiffening rib, and means to secure the member in position on the shoe.
5. A shoe guard including a metallic shield adapted to fit over the instep portion of a shoe and having a width greater than the shoe, a flexible fabric member secured adjacent its side edges to the side edges of the metallic shield and adapted to rest on the shoe, said member and shield being arranged to project forwardly over and to completely cover the toe of the shoe, said shield being held away from the shoe by said member and being arched to lie in spaced relation to the member above the shoe, and means to secure the member in position on the shoe.

In testimony whereof I affix my signature.
ALBERT A. STRAUSS.
